UNITED STATES PATENT OFFICE.

GEORGE E. BERNECKER, OF MILWAUKEE, WISCONSIN, ASSIGNOR, BY MESSE ASSIGNMENTS, TO RECORD NEEDLE & MANUFACTURING CO., OF MILWAUKEE, WISCONSIN.

CUTTING DEVICE.

1,319,689.

Specification of Letters Patent. Patented Oct. 28, 1919.

Application filed September 4, 1917. Serial No. 189,544.

To all whom it may concern:

Be it known that I, GEORGE E. BERNECKER, a citizen of the United States, residing at Milwaukee, in the county of Milwaukee and State of Wisconsin, have invented new and useful Improvements in Cutting Devices, of which the following is a specification:

This invention relates to cutting devices of the type employed for repointing fiber needles used in sound reproducing machines.

The needles used in sound reproducing machines are usually made of metal or wood fiber. One of the advantages of the fiber needle is that it can be readily repointed by cutting or trimming the end of the needle. This invention provides a so-called needle cutter for repointing fiber needles and other needles that are capable of being repointed by a cutting or trimming operation.

One object of the invention is to provide an improved needle cutter for repointing or sharpening the needles of sound reproducing machines.

Another object is to provide a needle cutter which will so trim the needle as to produce a sound reproducing point of highest efficiency.

Another object is to provide a needle cutter having means for engaging the point and beveled end of the needle and directing the same into the cutter in the proper position.

Another object is to provide a fiber needle cutter which will trim the needle beginning at the heel and terminating at the point thereof.

Other objects will appear as the specification proceeds.

One embodiment of the invention is illustrated in the accompanying drawing. The views of the drawing are as follows:

Figure 1 is a plan view of the needle cutter:

Fig. 2 is a vertical longitudinal section taken on the line 2-2 of Fig. 1;

Fig. 3 is a transverse vertical section taken on the line 3-3 of Fig. 1; and

Fig. 4 is a view similar to Fig. 3, show-

ing the parts of the cutter in the position which they assume when a needle is inserted.

The needle cutter illustrated in the drawing will be specifically described, but the specific description is for illustrative purposes and should not be construed in a limiting sense.

The needle cutter comprises a pair of levers 1 and 2, having relatively broad members 1' and 2' which are pivotally connected by means of a screw 3. The levers 1 and 2 are provided with openings 4 and 5 through which the fingers of the operator may be inserted to actuate the levers.

The cutting end of the member 1' is provided with an opening 6 to receive the needle to be repointed. As the fiber needles in practice are usually made triangular in cross section, the opening 6 is in the present instance made triangular in shape, as shown in Fig. 1. The opening 6 is of proper size to receive the needle and to hold it firmly during the cutting operation.

The axis of the opening 6 is inclined rearwardly with respect to the cutting plane so that the needle will be cut in a plane 75 which is oblique to the longitudinal axis of the needle. Expressed in a different way, the opening 6 is inclined downwardly and forwardly from the pivot 3. This will produce the sound reproducing point at the 80 lowermost corner of the needle in the well-known manner.

A depression or guideway 7 is provided in the member 1' at the entrance to the opening 6 to guide the needle into the opening. 85 The lower surface of the guideway 7 is slightly inclined as shown in Fig. 2. When the needle is inserted in the opening 6, the oblique end of the needle is placed upon the inclined guiding surface 7 and then the 90 needle is moved bodily into the opening. When the needle is inserted in this manner it will always assume such a position in the opening that the cut will be parallel to the oblique end surface of the needle. 95

The cutting end of the member 2' is recessed on its inner surface, as shown at 17, and in this recess there is positioned a knife

blade 8. The knife blade is held in position due to its being located between the two levers and due to the walls of the recess and the screw 3, which passes through an opening in the knife blade. The knife blade 8 is so positioned that when the levers 1 and 2 are actuated the cutting edge of the knife blade passes by the inner extremity of the opening 6. The cutting edge 9 of the knife 10 blade is curved or inclined so that it will produce a draw-cut, the cutting operation beginning at one rear corner of the needle and terminating at the point thereof.

The cutting end of the member 2' is provided with an opening 10 at the rear of the knife blade 8, through which the shavings from the needle escape. The opening 10 is so positioned that the cutting edge 9 of the knife blade extends across the opening 20 and leaves a clearance 11 through which the shavings may be discharged, as shown in Fig. 1.

The member 1' is provided with a slot 12 into which projects a pin 13 carried by the member 2'. The pin and slot limit the relative movement of the levers 1 and 2.

In the closed position of the members 1' and 2' the needle receiving opening 6, the knife blade 8, and the discharge opening 30 10 assume the relative positions shown in Fig. 3. When it is desired to re-point a needle, the needle is held in the position indicated by the dotted lines in Fig. 2, with the oblique end surface 15 of the needle 35 parallel to the inclined surface of the guideway 7. The needle is then moved toward the opening 6 and the oblique end surface of the needle will ride down the inclined surface of the guideway and direct the needle into 40 the opening 6. When the needle is inserted in this manner the cut will obviously be parallel with the oblique end surface of the needle, and therefore the needle may be re-pointed by removing only a small portion 45 from the needle. The guideway 7 permits the needle to be inserted in the cutter without the exercise of special care by the operator to have the needle in such a position that the cut will be made parallel to the surface 50 15, as he will instinctively place the oblique end of the needle upon the surface 7 in positioning the needle.

After the needle is positioned the levers 1 and 2 are moved apart and the needle may 55 then be moved to its innermost position against the bottom surface 16 of the recess 17, as shown in Fig. 4. A small portion of the needle will then project under the cutting edge of the knife. The surface 16, 60 therefore, acts as a gage to determine the amount of the needle that will be removed during the cutting operation. The surface 16 is so located that the needle will project but a slight distance beyond the edge of the

knife blade so that but a very thin shaving 65 will be removed from the needle. As the shaving is removed it is discharged through the opening 10. The trimming of the needle in the above described manner obviously produces a new point at the lowermost corner of the needle. 70

The actuating ends of the levers 1 and 2 are preferably offset with respect to the axis of the cutting ends so that when the cutter is held in front of the operator it will be more 75 convenient to insert the needle in the opening 6.

The knife blade 8 lies in a plane which is substantially parallel with the plane of the levers, and, therefore, the device operates 80 with a scissor-like action. The knife blade may be readily removed and resharpened or replaced by a new blade by removing the screw 3. The levers 1 and 2 may then be separated and the knife blade may be removed from the recess 17. 85

The cutter is made of a minimum number of parts and is therefore inexpensive to manufacture. It is simple in construction and easy to manipulate. 90

The cutter will re-point the needle by removing therefrom a very thin shaving and this is rendered possible by the fact that the knife produces a draw-cut on the needle and in no way injures the fibers thereof. 95

It will be noted that the knife blade starts the cut at the heel of the needle and cuts toward the point thereof. This produces a sound reproducing point of much better quality than if the cut were started at the 100 point. Furthermore the cut is in the direction of the downward inclination of the opening 6. Therefore during the cutting operation there is a tendency for the needle to be drawn farther down into the opening 105 instead of being pushed out of the same.

Very little effort is necessary to cut the needle due to the fact that the opening 6 and the cutting edge of the knife are located close to the pivot 3, whereas the points at 110 which pressure is applied to the levers 1 and 2 are located relatively far from the pivot 3. A good leverage is therefore obtained and this, in combination with the draw-cut feature, renders it possible to trim the needle 115 with a minimum amount of effort.

Although the cutter herein disclosed is intended primarily for cutting or re-pointing sound reproducing needles, it may be found useful for cutting or trimming other articles. 120

What I claim is:—

A cutting device comprising a pair of pivoted levers, one of which has a portion which moves over a corresponding portion 125 of the other lever, the inner surface of one of said lever portions being recessed to form a shoulder, a knife blade located in and

occupying a portion of said recess and having an edge in engagement with said shoulder, the other lever portion having an opening for receiving an article to be cut, 5 so that the extremity of said article may abut against the bottom surface of said recess, and said knife carrying portion being

provided with an opening through which the cut portion of said article may be discharged.

10

In witness whereof, I have hereunto subscribed my name.

GEORGE E. BERNECKER.
